UNITED STATES PATENT OFFICE.

JOHN R. RAY AND WILLIAM E. SANKEY, OF SALEM, MISSOURI.

TIME STOCK-FEEDER.

SPECIFICATION forming part of Letters Patent No. 760,482, dated May 24, 1904.

Application filed December 21, 1903. Serial No. 186,137. (No model.)

To all whom it may concern:

Be it known that we, JOHN R. RAY and WILLIAM E. SANKEY, residents of the city of of Salem, county of Dent, and State of Mis- 5 souri, have invented a new and useful machine for feeding horses and other stock at a certain determinate hour by clockwork, to be called an "automatic time stock-feeder;" and we do hereby declare that the following is a full, 10 clear, and exact description of the construction and operation of the same, reference being had to the annexed drawings, making a part of this specification.

This invention relates to new and useful im- 15 provements in automatic time stock-feeding apparatus, and comprises means whereby a hinged door may be automatically released by means of an alarm attachment to a clock at a predetermined moment, whereby food for ani- 20 mals may be automatically fed into a feeding-trough or manger, and in the provision of spring-actuated means for returning the door to its normal position.

The invention consists, further, in various 25 details of construction and combinatons and arrangements of parts, which will be hereinafter fully described and then specifically defined in the appended claim.

We illustrate our invention in the accompa- 30 nying drawings, which, with the letters of reference marked thereon, form a part of this application, and in which drawings, Figure 1 is an elevation of our improved apparatus. Fig. 2 is a side view.

Reference now being had to the details of the drawings by letter, A designates a chute through which food is adapted to be passed, and B designates a door which is hinged at C to the inner wall of the chute.

40 *a'* designates an arm which projects through the wall of the chute and has a spring O secured thereto, which is fastened to a pin O', adapted to be held in a hole in the wall of the chute.

45 Supported upon a bracket-arm upon the side of the chute is a clock H, having an alarm attachment, and K designates a key which winds the spring mechanism of the alarm apparatus.

Projecting from said key is a rod N, which is adapted to rotate with the key as the same is 50 turned in one direction or the other, and Q designates a stop which is positioned in the path of said rod N and against which the latter strikes to limit its throw in one direction or the other.

55 D designates a spring-pressed bolt which is mounted in the wall of the chute, and projecting from said bolt is a finger D', to which a spring E is fastened, which in turn is secured to the wall of the chute, as shown. A cord F 60 is fastened to an eye at the end of said bolt, and its other end is secured to the shank portion of the winding-key K and is designed to wind about the key for the purpose of withdrawing said bolt, the forward end of which 65 is positioned underneath and adapted to support the hinged door when the same is weighted down by means of the food resting upon the same.

In operation our alarm apparatus is set so 70 that the food may be fed to the stock at any hour, and as the spring of the alarm apparatus begins to unwind the key K, turning in the winding-post, will cause the cord F to wind upon the post K and withdraw the bolt 75 D from underneath the free swinging edge of the door, allowing the food to fall down through the chute. After the food has fallen and the door is relieved of its weight the spring O will cause the door to resume its nor- 80 mal horizontal position. The bar N, coming in contact with the stop Q, will cause the post to stop its rotary movement, thereby allowing the bolt to be withdrawn only a sufficient distance to allow the free swinging edge of 85 the door to pass. As the door D returns to its normal position the bolt will be retracted to allow the same to pass, after which it will resume its normal position and support the swinging edge of the door.

90 Having thus fully described our invention, what we claim as new, and desire to secure by Letters Patent, is—

An automatic time stock-feeder comprising a feeding-chute, a door hinged therein, an arm 95 projecting from said door through the wall of

said chute, a spring fastened to said arm and a pin to which said spring is secured, a spring-
pressed bolt adapted to support the free
swinging edge of said door, an alarm appara-
tus with winding-post, cords fastened to said
bolt and adapted to wind about said post, an
arm projecting from said post and a stop
against which said arm is adapted to contact

to limit the outer movement of said bolt, as
set forth.

JOHN R. RAY.
WILLIAM E. SANKEY.
